UNITED STATES PATENT OFFICE.

RUDOLPH H. SCHEIBERT, OF CINCINNATI, OHIO.

CRANE SAFETY DEVICE.

1,304,381.

Specification of Letters Patent. Patented May 20, 1919.

Application filed October 4, 1918. Serial No. 256,787.

To all whom it may concern:

Be it known that I, RUDOLPH H. SCHEIBERT, a citizen of the United States, residing at Hartwell, Cincinnati, Hamilton county, Ohio, have invented certain new and useful Improvements in Crane Safety Devices, of which the following is a specification.

This invention, pertaining to crane safety devices, relates to devices for automatically arresting the travel of the crane bridge along the crane track so as to render safe for workmen that portion of the floor which in the absence of the safety devices might 15 be traveled over by the crane bridge with its hook or a suspended load.

The invention will be readily understood from the following description taken in connection with the accompanying drawings in 20 which:

Figure 1 is an elevation of the outside face of a pair of the columns supporting the crane track.

Fig. 2 an inside view of one of the columns:

Fig. 3 a vertical section of a portion of the crane track, in the plane of line *a* of Figs. 1 and 2:

Fig. 4 a similar vertical section in the plane of line *b* of Fig. 1: and

Fig. 5 a diagram of an exemplifying circuit.

In the drawings:

1, indicates a series of columns arranged 35 to support the crane runway:

2, one of the longitudinal rails of the crane runway, supported by the series of columns 1:

3, the crane-bridge mounted to travel on 40 the crane runway and adapted to have the usual hoisting trolley travel upon it transversely of the runway:

4, one of the conductors supported parallel with the rail 2:

45 5, the second similar conductor:

6, a shoe carried by and traveling with the crane-bridge and making constant contact with conductor 5:

7, a second shoe carried by the crane-bridge and making constant contact with conductor 4:

8, one of the conductors, leading from the shoe 6, and adapted for connection with the motor on the transversely traveling trolley:

55 9, the other conductor, adapted to place

the shoe 7 in communication with the trolley motor:

10, one of the incoming mains to convey current to conductor 5:

11, the other incoming main, adapted to 60 convey current to conductor 4: and

12, an automatic over-load circuit-breaker disposed in main 11, this over-load circuit-breaker being preferably mounted on one of the columns.

The parts thus far referred to may be as usual in electric traveling cranes and are subject to any of the usual modifications in such cranes. Current from the mains 10 and 11 supplies current to the conductors 4 and 70 5, which current is taken up by the shoes and transmitted through conductors 8 and 9 to the motor of the trolley.

Proceeding with the drawings:

13, indicates short conductors placed at 75 intervals along the crane runway, parallel with the conductors 4 and 5, these short conductors being adapted, as the crane moves along the runway, to make contact with the shoe 7:

14, a conductor leading downwardly from each of the short conductors 13:

15, a conductor leading downwardly from conductor 5: and 16, a normally open switch placed, preferably, near the foot of each 85 of the columns and adapted to connect conductors 14 and 15.

The switches 16 and the automatic circuit-breaker 12 are to be preferably arranged on the columns and within suitable inclosing 90 casings. There may be one of the short conductors 13 at each of the columns, each having its switch 16.

Normally switches 16 are open, and short conductors 13 are without office, the shoe 7 95 passing over them idly. But if it happens that workmen be engaged on the runway or on the floor at some certain point passed over by the traveling bridge, and there would

ordinarily be danger that those workmen 100 would be struck by the hook or suspended load carried by the traveling bridge, it is simply necessary to close the switch 16 at a column between the territory to be protected and the traveling bridge. The closing 105 of such switch causes the motor of the crane to be short circuited when the bridge reaches the appropriate one of short conductors 13, thus rendering it impossible for the bridge

to travel over the protected territory. If 110

the bridge is subject to momentum enough to cause it to encroach upon the protected territory after the current of its motor is short circuited, such possibility may be guarded 5 against by utilizing the switch 16 at a point farther from the protected territory. The automatic circuit-breaker 12 may guard the circuit when any one of the switches 16 is closed.

10 I claim:—

1. A crane safety device comprising, a crane runway, a bridge fitted to travel thereon, a pair of conductors arranged parallel with the runway, shoes carried by the bridge 15 and adapted to traverse the two conductors, conductors adapted to lead current from the shoes to a motor carried by the bridge, mains connected with the pair of conductors, a series of short conductors arranged along 20 the runway and adapted to be engaged by one of the shoes of the bridge as the bridge reaches one of the short conductors, stations arranged accessible from the floor along under the runway, conductors leading 25 from the stations to the respective short conductors and to one of the pair of conductors, and a switch arranged at each sta-

tion to control the action of the short conductors, combined substantially as set forth.

2. A crane safety device comprising, a 30 crane runway, a bridge fitted to travel thereon, a pair of conductors arranged parallel with the runway, shoes carried by the bridge and adapted to traverse the two conductors, conductors adapted to lead current from the 35 shoes to a motor carried by the bridge, mains connected with the pair of conductors, a series of short conductors arranged along the runway and adapted to be engaged by one of the shoes of the bridge as the bridge 40 reaches one of the short conductors, stations arranged accessible from the floor along under the runway, conductors leading from the stations to the respective short conductors and to one of the pair of conductors, a switch arranged at each station to control the action of the short conductors, and an automatic circuit-breaker disposed in the 45 mains, combined substantially as set forth.

RUDOLPH H. SCHEIBERT.
